CLAIM

(22) Filed: **Jan. 30, 2006**

The ornamental design for a top panel for microwave introduction window of a plasma processing apparatus, as shown and described.

(30) **Foreign Application Priority Data**

DESCRIPTION

Jul. 29, 2005 (JP) 2005-022104

FIG. 1 is a front view of a top panel for microwave introduction window of plasma processing apparatus showing our new design;

(51) **LOC (9) Cl.** **15-09**

FIG. 2 is a rear view thereof,

(52) **U.S. Cl.** **D15/138**

FIG. 3 is a right side view thereof,

(58) **Field of Classification Search** D7/586,

FIG. 4 is a left side view thereof,

D7/587, 501, 553.6, 600.4; D8/70, 74; D9/445,

FIG. 5 is a top plan view thereof,

D9/454, 456, 139, 158; D15/133, 144.1,

FIG. 6 is a bottom plan view thereof,

D15/199, 122, 138, 139; 117/103; 118/723 AN,

FIG. 7 is a sectional view taken along line 7—7 of FIG. 5;

118/723 ME, 723 MP, 723 MW, 723 E, 723 ER;

FIG. 8 is an enlarged sectional view taken along line 8—8 of FIG. 7;

216/69, 67; 257/E21.252, 252, 629, 631,

FIG. 9 is a perspective view thereof; and,

257/E39.001; 427/562, 571, 575; D1/126,

FIG. 10 is an enlarged detail view of the circled area 10 in FIG. 9.

D1/128; D6/455; D13/122, 138, 177, 182;

The broken line showing of the top panel for microwave introduction window of a plasma processing apparatus is included for the purpose of illustrating portions of the microwave introduction window of a plasma processing apparatus and forms no part of the claimed design.

D18/17; 156/242, 345; 175/374, 434; 204/298.38;

219/420—424, 523, 530, 541, 544; 264/328.14,

1 Claim, 4 Drawing Sheets

264/328.15, 328.16; 313/231.31; 315/111.21;

407/113—118; 408/145; 425/547—550, 564,

425/566, 570; 451/540—548; 700/121, 123

See application file for complete search history.
